(57) CLAIM

I claim the ornamental design for a pet bandana with zipper pocket, as shown.

DESCRIPTION

FIG. 1 is a perspective view of the pet bandana with zipper pocket;

FIG. 2 is a front view of the pet bandana with zipper pocket;

FIG. 3 is a back view of the pet bandana with zipper pocket;

FIG. 4 is a right-side view of the pet bandana with zipper pocket;

FIG. 5 is a left side view of the pet bandana with zipper pocket;

FIG. 6 is a top view of the pet bandana with zipper pocket;

FIG. 7 is a bottom view of the pet bandana with zipper pocket;

FIG. 8 is a front view of the pet bandana with zipper pocket with the pocket flap raised; and,

FIG. 9 is an environmental view of the pet bandana with zipper pocket.

Broken lines illustrate environmental features and form no part of the claimed design.

1 Claim, 5 Drawing Sheets
